UNITED STATES PATENT OFFICE.

HUGH M. BRANHAM, OF BROOKLYN, NEW YORK.

DEPTH GEAR FOR TORPEDOES.

1,423,179.

Specification of Letters Patent. Patented July 18, 1922.

Application filed March 25, 1921. Serial No. 455,539.

To all whom it may concern:

Be it known that I, HUGH M. BRANHAM, a citizen of the United States, residing at Brooklyn, New York, have invented new and 5 useful Improvements in Depth Gears for Torpedoes, of which the following is a specification.

This invention relates to improvements in torpedoes and more particularly to improvements in the depth control mechanism.

In order that a clearer perception of the present invention may be had it may be stated that during the test and runs of torpedoes it has been found that there was a 15 tendency for the torpedo to sink during the run which was believed to be caused in some cases by pressure leaks from the after-body of the torpedo into the depth spring cases. During a run the after body pressure exceeds 20 the pressure in the spring cases by an amount depending upon the strength of the exhaust gas springs and the depth of water in which the torpedo is running. Any leaks into the depth spring case increases 25 the pressure on the inner side of the diaphragm thus neutralizing the outside pressure and causing the torpedo to seek a lower level. As the torpedo goes down to a lower level the after-body pressure increases with 30 the depth of water and the leak into the spring case continues. The resulting tendency is for the torpedo to seek at all times a depth of several feet deeper than that at which it is intended to run. Even when the 35 stuffing boxes about the spring are carefully made until tight under pressure test before a run is actually made leaks sometimes develop during a long range shot because of the drying out process to which the packing 40 is subjected.

It is, therefore, one of the objects of the present invention to improve the construction of the spring case depth control mechanism whereby its operation is more reliable 45 and efficient.

A further object is to provide a mechanism of the above character of relatively simple and practical construction which may be easily manufactured and installed and 50 will not in any way materially affect the arrangement and disposition of the other parts of the torpedo now in general use by its substitution.

Other objects will be in part obvious and 55 in part hereinafter pointed out in connec-

tion with the accompanying sheet of drawings forming part of this disclosure wherein is shown in vertical longitudinal section a portion of the depth control mechanism.

Referring to the drawing in detail, 1 denotes one-half of the spring case, the other half being mounted at the opposite side on the support 2 and being of similar construction. This casing 1 rests upon a housing 3 containing the pivotally mounted spring balance member 4 carried by the diaphragm 5 which is exposed on its under side to the action or pressure of the water when the torpedo is submerged. As the pressure varies the diaphragm moves up 60 and down according to the depth and varies the tension upon the springs supported by the balance 4, one of which is indicated at 65 6. The tension on this spring is controlled by means of depth setting mechanism 7 of 70 well-known operation to those skilled in the art, modified and improved in construction so as to be entirely usable in the proposed modification of the depth control mechanism. 75

As previously stated one of the main objections was due to the leakage of pressure in the after-body through the various joints or the opening through which the depth control setting mechanism passed to increase 80 the pressure upon the diaphragm 5 thereby effecting the depth at which the torpedo was intended to run. In order to overcome this objection there is interposed 85 between the member 8 at the lower part of the depth setting mechanism and a bushing 10 screwed into the depth spring casing, a sylphon 11, the sylphon being sweated to the nut 8 at one end and to the bushing or collar 10 at the other end thereby preventing 90 a leakage of pressure to the casing 3 containing the spring balance. This diaphragm does not move at any time except when the depth setting mechanism is actuated, the nut 8 being free to move up and 95 down under that operation, the spring 6 is, of course, free to expand and contract as the movement of the diaphragm takes place. To further insure against leakage of pressure in the after-body to the casing 3 a 100 stuffing box 12 is provided about the shaft 13 of the depth setting mechanism and an asbestos wrapping 14 is applied at the lower end or point of connection between the housing 3 and casing 1 as well as around the 105 110

upper portion of the spring case as in former proven constructions.

From the above it will be seen that the pressure leaks are positively excluded from the inner side of the diaphragm and the only movement of the sylphon occurs when the depth setting is changed. While the torpedo is running the sylphon bellows do not work with the change in length of the spring. Under such conditions the sylphon will not be subjected to those failures now occurring in the reducer sylphon where the constant working of the bellows leads to hardening and cracking.

The invention is of simple and practical construction, reliable and efficient in use and operation and adapted to accomplish, among others, all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and, therefore, such adaptations should and are intended to be comprehended within the meaning and range of equivalency of the following claims.

What I claim is:—

1. In a torpedo, in combination, a housing for the spring balance of the depth control mechanism, a spring within the housing, means for adjusting the tension of the spring and means interposed between the adjusting means and the housing for excluding the pressure of gases in the after-body from the interior of said casing. 35
2. In a torpedo, in combination, a casing, a spring balance housed therein, depth setting means partially within and adjustable from without said casing, a spring interposed between said depth setting means and the spring balance and an expandible member interposed between the depth setting means and the housing. 40
3. In a torpedo, in combination, a casing, a spring balance housed therein, depth setting means partially within and adjustable from without said casing, a spring interposed between said depth setting means and the spring balance, an expandible member interposed between the depth setting means and the housing, said member comprising a corrugated sylphon secured in an air tight manner to said depth setting mechanism and the casing. 45

Signed at Brooklyn, New York, this 14th 50 day of February 1921.

H. M. BRANHAM.
